US00D417161S

United States Patent [19]

Stasz et al.

[11] Patent Number: Des. 417,161

[45] Date of Patent: ** Nov. 30, 1999

[54] **ELECTRONIC TEMPERATURE/PRESSURE TRANSDUCER**

[75] Inventors: **Peter Stasz**, St. Paul; **David Mathews**, Blaine; **Charles Bille**, White Bear Lake, all of Minn.

[73] Assignee: **Dymedix Corporation**, Minneapolis, Minn.

[**] Term: **14 Years**

[21] Appl. No.: **29/096,698**

[22] Filed: **Nov. 18, 1998**

[51] LOC (6) Cl. **10-04**

[52] U.S. Cl. **D10/57; D10/52**

[58] Field of Search D10/52, 57, 60; 374/141, 151, 159, 161, 162, 208

[57] CLAIM

The ornamental design for an electronic temperature/pres-
sure transducer, as shown and described.

DESCRIPTION

FIG. 1 is a front view of an electronic temperature/pressure transducer showing my new design;

FIG. 2 is a rear view thereof;

FIG. 3 is front edge view thereof; and,

FIG. 4 is a side edge view thererof.
